(57) **CLAIM**

The ornamental design for a console for controlling a surgical robot, as shown and described.

DESCRIPTION

FIG. 1 is a top, right-side, front perspective view of a console for controlling surgical robot;

FIG. 2 is a top, left-side, rear perspective view of the console for controlling surgical robot of FIG. 1;

FIG. 3 is a left-side elevation view of the console for controlling surgical robot of FIG. 1;

FIG. 4 is a front elevation view of the console for controlling surgical robot of FIG. 1;

FIG. 5 is a right-side elevation view of the console for controlling surgical robot of FIG. 1;

FIG. 6 is a back elevation view of the console for controlling surgical robot of FIG. 1; and,

FIG. 7 is a top plan view of the console for controlling surgical robot of FIG. 1.

The broken lines illustrate portions of the console for controlling surgical robot that form no part of the claimed design.
